UNITED STATES PATENT OFFICE.

MAUD H. STAFFORD, OF NORFOLK, VIRGINIA.

MUFF-HOLDER.

1,332,449.

Specification of Letters Patent.

Patented Mar. 2, 1920.

Application filed November 18, 1919. Serial No. 338,959.

To all whom it may concern:

Be it known that I, MAUD H. STAFFORD, residing at Norfolk, in the county of Norfolk and State of Virginia, a citizen of the 5 United States, have invented certain new and useful Improvements in Muff-Holders; and I do hereby declare the following to be a full, clear, and exact description of the invention, such as will enable others skilled in 10 the art to which it pertains to make and use the same.

My invention relates to improvements in a muff holder and more particularly to a device for holding or supporting a muff when 15 not in use. The invention consists in the several features and in the construction, combination and arrangement of features as more fully described and claimed.

The object of the invention is to provide a 20 muff holder which will hold or support the muff in such manner that it will be kept in shape and may be easily and quickly removed from the holder or support when desired.

25 A further object is to provide a muff holder which is exceedingly simple, inexpensive and durable in construction and very convenient, and handy to use and attractive in appearance.

30 Referring to the drawings:—

Figure 1 is a front view.

Fig. 2 is a top plan view.

Fig. 3 is a cross-section on line 3—3 of Fig. 2.

35 Fig. 4 is a detail view of one end of the holder.

Fig. 5 is a top plan view partly in section of a modified form of holder.

40 Fig. 6 is a detail view of another modified form of holder.

In the drawings in which like reference characters denote like parts throughout the several views, 1 represents the muff holder or support, 2 the continuous flexible tube 45 thereof having a middle or central portion 3, end portions 4 and 5 and a snap button 6 or other suitable device for securing the flexible end portions 4 and 5 together at a central point 7 above the middle of the 50 holder or support.

The flexible tube may be made of cotton, silk, leather or any other suitable material which is flexible.

55 A rigid muff holding or supporting bar 8 is mounted in and inclosed by the middle portion 3 of the flexible tube 2 and which is

preferably made of wood, but which may be made of metal or any other suitable material, and 9 represents lines of stitching extending across the flexible tube at points 10 60 just beyond the ends of the holding or supporting bar 8, for the purpose of closing the tube at those points and preventing the endwise movement of the supporting bar 8. The supporting bar 8 is provided with 65 smooth, rounded ends 11 for the purpose of preventing it from wearing or tearing the fabric of the flexible tube.

In Fig. 5 a modified form of holder is shown in which snap buttons 11' are used on 70 the flexible tube at each end of the bar 8 to retain the same in place in the flexible tube instead of the stitches 9.

In Fig. 6 another modified form of holder is shown in which the bar 8 is held in place 75 in the flexible tube by means of ribbons 12, tapes or the like, which are tied around and compress the flexible tube at a point just beyond the ends of the bar and hold the same in the tube.

80 In use it is only necessary to separate the end portions 4 and 5 by disengaging the snap button and insert the muff on the middle or central portion 3 of the holder or support and then bring the two end portions together again and secure them by means of the snap button and then hang the holder on a nail or hook in a closet or other convenient place until it is desired to use the muff again. It will be found that by the use of this 90 holder or support that the muff will always be where it can be found within easy reach and prevented from falling on the floor and getting soiled or full of dust and dirt.

95 I do not wish to be understood as limiting myself to the specific details of construction and arrangement as herein described and illustrated, as it is manifest that variations and modifications may be made in the features of construction and arrangement, in 100 the adaption of the device to various conditions of use, without departing from the spirit and scope of my invention and improvements. I therefore reserve the right to all such variations and modifications as 105 properly fall within the scope of my invention and the terms of the following claims.

What I claim is:—

1. A muff holder, comprising a continuous flexible tube having a middle portion and 110 end portions, a rigid supporting bar mounted in the middle portion, means for closing

the flexible tube at each end of the bar to prevent endwise movement of said bar and means for detachably securing said end portions of the flexible tube together.

5. 2. A muff holder, comprising a continuous one piece flexible tube having a rigid muff supporting bar mounted on and inclosed by the middle portion of the flexible tube, means for closing the flexible tube to prevent 10 the endwise movement of the said bar and means for detachably securing the ends of the flexible tube together.

3. A muff holder, comprising a continuous flexible tube having a rigid muff supporting 15 bar mounted therein, stitching extending

across and closing the flexible tube adjacent to the ends of the said bar to prevent the endwise movement of the same and means for securing the ends of the flexible tube together.

4. A muff holder, comprising a flexible tube having a muff supporting bar mounted in the middle portion thereof, means for closing the flexible tube adjacent the ends of said bar to prevent the endwise movement 25 thereof and means for securing the ends of the flexible tube together.

In testimony whereof I have affixed my signature:

MAUD H. STAFFORD.
